UNITED STATES PATENT OFFICE.

JOHN REGAN, OF NEW BEDFORD, MASSACHUSETTS, ASSIGNOR TO CROMPTON & KNOWLES LOOM WORKS, OF WORCESTER, MASSACHUSETTS, A CORPORATION OF MASSACHUSETTS.

WARP-STOP-MOTION CLAMP.

Application filed June 28, 1923. Serial No. 648,353.

To all whom it may concern:

Be it known that I, JOHN REGAN, a citizen of the United States, residing at New Bedford, in the county of Bristol and State 5 of Massachusetts, have invented a new and useful Warp-Stop-Motion Clamp, of which the following is a specification.

This invention relates to a clamp designed for use in connection with the general type 10 of stop motion shown in my prior Patent No. 1,265,112 issued May 7, 1918. When this type of stop motion is used in broad looms it is found desirable to provide lateral support for the vibrator bars and drop 15 wire spacing bars at one or more intermediate points, so that lateral or swinging movement of the bars may not interfere with the operation of the stop motion and furthermore so that the weight of the relatively 20 small vibrator bars may not cause the bars to bend or sag excessively between their end supports. Clamps for this general purpose are shown in my prior Patents No. 1,307,022, issued June 17, 1919, and No. 25 1,355,909, issued October 19, 1920.

It is the object of my invention to improve the clamp shown in my prior Patent No. 1,307,022 by certain changes in the construction thereof which will be hereinafter 30 described and more particularly pointed out in the appended claims.

A preferred form of my invention is shown in the drawings in which

Fig. 1 is a side elevation of my improved 35 clamp, the vibrator and spacing bars of a stop motion being shown in section;

Fig. 2 is a sectional elevation taken along the line 2-2 in Fig. 1; and

Fig. 3 is a sectional plan view taken 40 along the line 3-3 in Fig. 1.

Referring to the drawings, I have shown my invention as applied to a six bank stop motion having six vibrator bars 10 and seven separator bars 11. The drop wires W 45 are positioned as indicated by dotted lines in Fig. 1, the different banks of wires being separated by the bars 11, and each wire is provided with an opening through which extends one of the vibrator bars 10.

50 For further details of the construction and operation of the stop motion, reference is made to my prior patent above noted.

My improved warp stop motion clamp comprises a center member 12, and an upper

clamping bar 13 and lower clamping bar 14 55 both pivoted to the member 12. The member 12 is provided with slots or recesses 15 for the separator bars 11 and also with semi-circular notches or recesses 16 in its upper edge cooperating with similar recesses 17 in the upper bar 13 to form substantially circular openings through which the vibrator bars 10 may extend. The bars are thus supported by the members 12 and are held from lateral movement by the member 12 and clamping bar 13, but at the same 60 time they are left free for oscillating movement in the usual operation of the stop motion.

A hook bolt 18 extends through a lug or 70 ear 19 on the bar 13, the hook end 20 of the bolt 18 being received in a notch 21 in the lower edge of the lower clamping bar 14. A nut 22 is threaded on the bolt 18 and provides means for drawing the parts 75 firmly together. The bars 13 and 14 are pivoted to projecting portions 23 of the member 12 and the bar 13 is preferably provided with depending spaced projections 25 (Fig. 2) adapted to embrace the upper 80 edge of the member 12 and the lower bar 14 is similarly provided with upwardly extending projections 26 (Fig. 1) for the same purpose. The provision of these projections 25 and 26 assists greatly in laterally aligning 85 the parts and preventing dislocation thereof. The upper face of the bar 14 is preferably widened at 27 to provide an additional bearing surface under the end separator bar 11^a, as the clamping pressure 90 is largely applied at this point.

Having thus described my invention and the advantages thereof, I do not wish to be limited to the details herein disclosed otherwise than as set forth in the claims but 95 what I claim is:—

1. A warp stop motion clamp comprising a center member, upper and lower clamping bars pivoted to said center member, and means to bind said parts together, certain 100 of said parts having spaced projections at their free ends embracing other parts to preserve the lateral alignment thereof.

2. A warp stop motion clamp comprising a center member, upper and lower clamping bars pivoted to said center member, and means to bind said parts together, said 105 lower bar and said center member having

co-operating portions near their free ends effective to laterally align said parts when in clamping position.

3. A warp stop motion clamp comprising a center member, upper and lower clamping bars pivoted to said center member, and means to bind said parts together, said upper and lower bars having spaced projections embracing said center member when the parts are drawn together and preserving the lateral alignment thereof.

4. A warp stop motion clamp comprising a center member, upper and lower clamping bars pivoted to said center member, and means to bind said parts together, said center member and said upper member hav-

ing co-operating recesses in their adjacent edges forming substantially circular openings for the vibrator bars of the stop motion.

5. A warp stop motion clamp comprising a center member, upper and lower clamping bars pivoted to said center member, and means to bind said parts together, said lower member having a portion of its upper bar-supporting face substantially widened adjacent its free end to provide increased bearing surface for the outside separator bar supported thereby.

In testimony whereof I have hereunto affixed my signature.

JOHN REGAN.
